DOOR LATCH

Robert C. Cerf, Los Angeles, Calif., assignor to
Pacific Plastic and Manufacturing Company,
Los Angeles, Calif., a corporation of California

Application February 10, 1945, Serial No. 577,176

3 Claims. (Cl. 292—359)

1

This invention relates to door latches and in particular to locking means for the latch bolt.

One object of the invention is to provide a locking means for a knob-and-spindle-actuated latch which is simple in construction, easily assembled, and easily applied to a door, and is reliable and convenient in use.

Another object is to provide improved means for locking latches operable from one side only of a door.

Still another object is to provide a locking device for latches operable generally from one side of the door with provision for emergency releasing of the locking means from the opposite side of the door.

These and other objects are attained by my invention which is hereinafter described, reference being made to the accompanying drawing in which

Fig. 1 is a front elevational view of a portion of a door provided with a door latch embodying my invention;

Fig. 2 is a door-edge elevational view of the door and latch shown in Fig. 1, portions being shown in section;

Fig. 3 is a cross-sectional view taken on the line 3—3 of Fig. 2;

Fig. 4 is a plan view of the rocker member and the rocker member base;

Fig. 5 is an edge view of the rocker assembly shown in Fig. 4;

Fig. 6 is a side view of a preferred knob and spindle latch mechanism.

In the preferred embodiment shown in the drawing, a portion of a door 11 is shown, in which is mounted a knob-and-spindle-actuated retractable latch bolt device. A preferred form is described and shown, consisting of a latch case 12, having a latch bolt 13 slidably mounted in the case and normally held in extended position by the spring means 14 acting against the inner end of the bolt and against a partition member 15 affixed to the sides of the latch case 12. The latch bolt 13 at its inner end is provided with connecting lugs 16 which are linked into slots in a latch-retracting member 19 fitting inside the case, this latch-retracting member having an upper and lower portion sliding respectively above and below the partition member 15; and the actuating wing 20 attached to the hub 21, which is engaged in its rectangular sectioned axis by the square sectioned spindle 22. Slots 23 and 24 are provided in the latch retracting member 19 respectively in the upper and lower portions so that the wing 20 engages either the upper or the lower

2

portion (which are interconnected as a unit by the end portion 17), when the spindle 22 is turned in either direction, thus retracting the latch bolt 13 by either turning movement of the spindle.

The spindle 22 extends through the door on either side thereof, the left hand knob 25 and the right hand knob 26 (as shown in Figs. 2 and 3) being respectively the outside and the inside of the door, the knobs 25 and 26 being attached to the spindle 22, for example, by the set screws 27. A rosette 28 is provided on the outside between the door and the shank of the knob 25, short screws 29 into the door holding the rosette 28 in place.

On the inside of the door, a rosette 30 is provided, which covers the latch locking mechanism as hereinafter described. The rosette 30 is removably attached, as by crimping, to the outer edge of a positioning member 31 which consists of a shallow cylinder having a base on which it is mounted on the side of the door and having two internally threaded lugs 32 extending into the door respectively above and below the latch case 12, these lugs serving to hold the locking device firmly to the door by means of the screws 34 in the threaded holes 33, the screw heads being positioned under the outside rosette 28. The rim 35 extends in opposite direction from the lugs 32, and is preferably provided with an opening 36 adapted to receive the locking bar 57 to more securely lock the turning of the spindle, and to permit the emergency release in the manner described below. The rim 35 is also conveniently notched at 38 for the lugs 49 in the rocker base plate 50 to position and prevent relative turning of the two parts.

The locking disk 40 which is adapted to rotate within the rim 35 of the positioning member 31 is provided with a hub 41 extending on both sides and adapted to rotate in the center hole 39 of the positioning member 31 as a bearing, and also on the other end to serve as a bearing and as a centering member for the rocker arm base plate 50. The opening 42 through the hub 41 is non-circular, usually square, to fit the spindle 22 for the knobs 25 and 26. The disk 40 turns with the spindle 22; it is provided with a notch 43 in the outer peripheral portion which, when the latch bolt 13 is extended and the knobs are "at rest," is in alignment with the locking opening 36 in the positioning member 31, and at times accommodates the locking bar 57.

The rocker base plate 50 is adapted to be attached by the lugs 49 in the rim openings or notches 38 of the positioning member 31. The

rocker member 51 consists of a disk portion 52 with extending arms 53 and 54 at diametrically opposite sides, and with edge or V-bearings 55 at positions intermediate the extending arms, these bearings being conveniently made by bending or crimping the disk, 52 as shown, to rest on the base plate 50. Hold-down tabs 56 attached to or punched out from the base plate 50 extend over the bearing edges 55 to keep the rocker 51 in place. Knobs or buttons 58 and 59 are attached respectively to the rocker arms 52 and 53, and these knobs or buttons extend through suitable holes 60 in the rosette 30, so that when one or the other is pressed, the rocker 51 is tilted correspondingly. The extreme end of the arm 53 is bent at right angles toward the positioning member 31 to form the locking bar 57, which, when the arm 54 is in the "down" position, extends through the notch 61 in the rocker base plate, which notch is orientated with the locking opening 36 in the positioning member 31, and also with the notch 43 in the locking disk 40 when the latch bolt 13 is in extended position and the knobs are "at rest." The locking bar 57 is so positioned and dimensioned that when the arm 53 of the rocker member is in the "down" position, it is withdrawn from the openings in the positioning member 31 and in the locking disk 40, so that the latter is free to move as the knobs 25 and 26 are turned in withdrawing the latch bolt.

To give more positive positioning of the locking bar 57 and to prevent accidental displacement thereof, the edges of the bar are provided with indentations 62 into which the ends or end portions of the wire springs 63 are engaged, one set of indentations corresponding to the fully locked position, and the other to the free position. The springs 63 are attached by the screws 64 and held in suitable position on the rocker base plate by the tabs 65.

It will be clear from the description that the knobs may be turned in either direction and the latch bar operated in the normal manner so long as the rocker 51 is tilted so that the locking bar 57 is in the "out" position because the locking disk 40 is then free to rotate; but when the rocker is tilted in the other position, by pressing the button 59 extending through the inside rosette 30, the locking bar then extends through the notch 43 of the locking disk 40 and into the opening 36 of the positioning member 31, and the spindle 22 may then not be turned because the hub 41 on disk 40 cannot be turned.

In order to provide for emergency unlatching of the door from the outside, even when locked from the inside by the locking device above described, an additional hole 66 may be, optionally, provided in the outer rosette 28, this hole registering with a hole 67 in the door and clearing the latch case 12, terminating beneath the opening 36 in the base of the positioning member 31, this opening being provided in the preferred form of my invention to give more secure locking of the spindle and for the purpose of this emergency unlatching means. A piece of wire, (not shown) or other tool, may be inserted through this hole to push the locking bar 57 out of the opening 36 and the notch 43 of the locking disk 40, thus permitting the spindle to be turned and the latch bolt 13 retracted, to unlatch the door.

While I have shown and described a preferred embodiment of my invention, it will be understood that it is not limited to all of the details shown, but is capable of modification and variation within the spirit of the invention and within the scope of the appended claims.

I claim:

1. In a door lock, locking means for a knob-and-spindle-actuated retractable bolt means operable from one side of a door at times to hold the spindle against turning, comprising a shallow cylinder positioning member concentric with the spindle attachable at its base to a door, a notched locking disk adapted to rotate within said positioning member and non-rotatably connected to said spindle, a covering disk non-rotatably attached to said positioning member having an opening adapted to receive a locking bar, rocker means rockably mounted on said covering disk, a locking bar extending parallel to the spindle from one end of said rocker means adapted at times to simultaneously engage the openings in said covering disk and the notch in said locking disk, and push button means affixed on opposite ends of said rocker means for rocking said rocker means to engage and disengage said locking bar.
2. In a door lock, locking means for a knob-and-spindle-actuated retractable bolt means operable from one side of a door at times to hold the spindle against turning, comprising a shallow cylindrical positioning member concentric with the spindle attachable at its base to a door and provided with an opening therethrough adapted to receive a locking bar, a notched locking disk adapted to rotate within said positioning member non-rotatably connected to said spindle, a covering disk non-rotatably attached to said positioning member having an opening adapted to receive a locking bar, rocker means rockably mounted on said covering disk, a locking bar extending parallel to the spindle from one end of said rocker means adapted at times to simultaneously engage the openings in said positioning member and said covering disk and the notch in said locking disk, and push button means affixed on opposite ends of said rocker means for rocking said rocker means whereby to engage and disengage said locking bar in the notch in said locking disk.
3. In a door lock, a knob-and-spindle-actuated retractable bolt means; and locking means operable from one side of a door at times to hold said spindle against turning, said locking means consisting of a shallow cylindrical positioning member concentric with said spindle attachable at its base to the door and provided with an opening therethrough adapted to receive a locking bar, a notched locking disk adapted to rotate within said positioning member and non-rotatably connected to said spindle, a covering disk attached to said positioning member having an opening adapted to receive a locking bar, rocker means rockably mounted on said covering disk, a locking bar extending parallel to the spindle from one end of said rocker means adapted at times to simultaneously engage the openings in said positioning member, covering disk and locking disk, and finger-operable means for rocking said rocker means to engage and disengage said locking bar with the notch in said locking disk.
